UNITED STATES PATENT OFFICE.

HUBERT WITTE, OF ST. LOUIS, MISSOURI, ASSIGNOR TO ST. LOUIS CAR COMPANY, OF ST. LOUIS, MISSOURI, A CORPORATION.

GUARD FOR STREET-CAR WINDOWS.

SPECIFICATION forming part of Letters Patent No. 792,951, dated June 20, 1905.

Application filed October 21, 1904. Serial No. 229,505.

To all whom it may concern:

Be it known that I, HUBERT WITTE, a citizen of the United States, residing in the city of St. Louis, in the State of Missouri, have 5 invented certain new and useful Improvements in Guards for Street-Car Windows, of which the following is a full, clear, and exact description, reference being had to the accompanying drawings, forming part of this specification.

My invention relates to a guard applied to the exterior of a street-car and extending across the car-window to prevent the protrusion of the arms or heads of persons occupying the car through the window-openings when the windows are open.

Figure I is an elevation of a car-window with my guard shown applied thereto. Fig. II is a vertical section of the guard. Fig. III is an enlarged vertical section taken through a portion of one of the window-posts and the upper end of one of the uprights of my guard.

A designates a window-sash, and B window-posts in which the sash fits.

25 1 designates the longitudinal rods of my guard, which are mounted in uprights 2, the uprights preferably corresponding in number to the number of window-posts at the side of the car. The uprights are hinged to brackets 30 3, secured to the window-posts above sill-edge. The upper ends of the uprights contain elongated openings 4.

5 designates plates set into the window-posts in a position corresponding to that occupied by the upper ends of the uprights 2 when they are elevated and in alinement with the window-posts.

35 6 designates turn-buttons swiveled at 7 (see

Fig. III) in the plates 5 and which are formed with an arm 8, that extends at an angle to the 40 axis of the swivel of the button. The inner edge of the arm of each button is flat-faced.

In the practical use of my guard it is held in vertical position with the uprights 2 resting against the window-posts, and while in 45 such position the arms of the buttons 6 are turned downwardly into the position seen in full lines in the drawings to clamp the guard-uprights and hold them. When it is desired to lower the guard, the buttons are rotated 50 into the position seen in dotted lines, Fig. III, thereby locating the arms of the buttons in alinement with the elongated openings 4 in the uprights, and the uprights may then be moved outwardly from the window-posts and 55 separated from the buttons. When the guard is again elevated, the buttons are again rotated to their normal pendent position to again sustain the guard, as before.

I claim as my invention—

The combination with the window-posts, of brackets secured to the outer faces of the window-posts, a window-guard comprising a series of uprights having their lower ends hinged to said brackets, longitudinal rods mounted 65 in said uprights and extending over a series of windows, and means for securing the upper ends of the uprights to the outer faces of the window-posts, said means being releasable to permit of the uprights and the rods 70 being swung outwardly from the window-posts, substantially as set forth.

HUBERT WITTE.

In presence of—

H. F. VOGEL,
E. I. ROBINSON.
